PLASTIC FURNITURE LEG TIP
Jerome T. Donahue, Rte. 2, Box 150, Thiensville, Wis.
Filed Nov. 19, 1958, Ser. No. 774,902
1 Claim. (Cl. 45—137)

This invention relates to a plastic furniture leg tip. While plastic furniture leg tips are old per se, considerable difficulty has been experienced in using such tips on metal furniture legs which have a relatively sharp cutting end or edge. The sharp edge of the metal leg inherently cuts through the plastic body of the tip to destroy it.

I have substantially completely eliminated this defect in prior art tips by thickening the bottom portion of the plastic tip body in an annular pattern around an internal shoulder on which I seat a fiberboard disk or washer which intervenes between the plastic body of the tip and the sharp edge of the metal leg. The sharp edge of the metal leg may score and gouge into the fiberboard washer, but it will not cut therethrough. Plastic furniture leg tips fabricated according to my invention will last indefinitely.

Other objects, features and advantages of the invention will appear from the following disclosure in which:

FIG. 1 is an axial cross section taken through a plastic furniture leg tip sleeved about a metal furniture leg.

FIG. 2 is a perspective view of the structure shown in FIG. 1.

FIG. 3 is a perspective view of the fiberboard washer.

FIG. 4 is a perspective view of a half section of plastic tip body.

According to the present invention a plastic furniture leg tip or cup is provided in its side wall 8 and near its bottom wall 9 with an internal shoulder 10 about which the plastic body is thickened in an annular pattern and on which a fiberboard or like disk or washer 12 is seated. The plastic tip is ensleeved or telescoped over the end of a metal furniture leg 13. The end 14 of the metal leg is conventionally sharply cut off in its manufacturing process to leave ends 14 with a relatively sharp cutting edge.

But for the fiberboard washer 12, the sharp edge 14 of the leg 13 would readily cut through the plastic body of

2

the tip 8 and destroy it. In the device of the present invention, however, the fiberboard washer 12 intervenes between the plastic cup and sharp edge of the leg end 14 to protect the plastic from being cut by the sharp edge of the leg. The sharp edge of the leg may gouge or score the fiberboard washer which has sufficient resistance, however, to prevent the sharp edge from cutting into the plastic.

The shoulder 10 is desirably spaced upwardly somewhat above the bottom wall 9 of the tip to provide a cavity 15 between the tip bottom wall 9 and the washer 12. The tubular wall of the metal leg 13, however, is aligned vertically with the thickened portion 11 of the plastic tip 8 and thus leg stresses are transmitted through the washer to the plastic body. Because of the recess 15, however, the tip interposes considerable resilience between the furniture leg 13 and the supporting surface such as floor 16.

As used in this specification and the appended claim, 20 fiberboard means both a pressed non-impregnated board made of wood fibers and a board made of vulcanized fibers impregnated with resinous material, and all equivalent thereof.

I claim:

25 The combination with a metal furniture leg having a tubular wall with a relatively sharp cutting edge, of a tip having a plastic body sleeved over the end of said leg, said tip having an internal shoulder aligned with 30 said wall and a cut-resistant washer seated on said shoulder and intervening between the sharp cutting edge of said wall and the plastic body of said tip, said shoulder being spaced above the bottom end of said tip to define a cavity between said bottom and said washer, said plastic body being thickened in the vicinity of the shoulder.
